POWER CONTROL

George M. Holley, Jr., Grosse Pointe, Mich., assignor to George M. Holley and Earl Holley

Application March 3, 1944, Serial No. 524,977

9 Claims. (Cl. 123—103)

1

The object of this invention is to regulate the throttle of a supercharged airplane engine in which the throttle is located in the air entrance leading to the supercharger.

The specific object is to regulate the supercharger pressure so that when the supercharger pressure exceeds the pressure of the atmosphere by a certain number of pounds per square inch, the air inlet throttle is closed so as to prevent the supercharger pressure from exceeding the number of pounds per square inch above the atmospheric pressure selected by the pilot.

The regulation of an engine by automatically controlling the number of pounds per square inch increase of the pressure of the supercharger and also the manual selection of the amount of this increase is old. One example of this is the French Patent No. 398,637 to Bihan et al., dated March 29, 1909. The defect of Bihan was that when the plane ascended into the air, there was a loss of power due to the fall in the density of the air. Hence, it is necessary, if such a loss is to be avoided, to obtain an increasing difference between the atmospheric pressure and the pressure generated by the supercharger with altitude. This pressure is commonly known as "gauge pressure." If the attempt is made to give a constant absolute pressure on the engine side of the supercharger, then because of the decrease in the exhaust back pressure the net result is that there is an increase of power with altitude at the rate of 1.2% per 1,000 feet, approximately. The greatest power, however, is needed when getting off the ground at sea level and, therefore, this is the opposite of what is desired.

I, therefore, propose to vary this increase in manifold air pressure with altitude so as to give the maximum supercharger pressure when taking off at sea level.

The figure shows the preferred form of my invention.

In the figure, 1 is the pilot's hand control. 2 is a link connecting it with a lever 3 which is connected through suitable operating means including the mechanism enclosed in casing A to a rod 4 which is connected to a throttle 5. Barometric element 6, connected through suitable operating means including the device B to a cam 7, controls the fulcrum 8 so that the position of the fulcrum 8 varies with altitude. Manual control modified by altitude is thus available. The roller 8 is mounted on a connecting rod 35 which slides in the stationary element 37 and which connects the roller 8 with a pin 36. Pin 36 is the fulcrum for the lever 3.

2

A and B are two servo motors of well known types. The lever 3 engages with a button 9 which in its turn engages with a compression spring 10 which engages with a flange of the rod 14. Rod 14 is connected to the diaphragm 11 which forms the right hand wall of a chamber 12 which is connected through pipe 18 with an inlet manifold 19 on the engine side of a supercharger 20 which is connected to the air entrance 21 in which is located the throttle 5. The rod 14 is so constructed and arranged as to act as a servo motor valve for operating the piston 13 which, when the rod 14 moves to the left, also moves to the left, compressing the compression spring 22.

Oil pressure is admitted through pipe 17 and escapes through passage 23. When the rod 14 is moved to the left, the ports in the rod 14 deliver the oil pressure into the chamber 24 on the right hand side of the piston 13 and the throttle 5 continues to open until the supercharger pressure in the inlet manifold 19 and in chamber 12 increases until the diaphragm 11 moves to the right restoring the valve rod 14 to its neutral position. Oil is allowed to escape from the left hand side of piston 13, that is, from chamber 25 through passage 26, past port in rod 14 to the oil outlet 23 when the valve rod 14 is left of the neutral position shown.

Before the engine begins to operate, there is no oil pressure and elements 15 and 16 are provided. Elements 15 and 16 are spring loaded and move down and engage with the rod 14. The rod 14 is connected directly to the piston 13 so that when this happens there is a rigid connection from rod 14 to the rod 4 so that the throttle 5 can be manually opened to start the engine.

When the oil pressure is admitted, the elements 15 and 16 are pressed upward, compressing the spring contained inside elements 15 and 16. When this happens, the rod 14 is free and, therefore, the piston 13 responds to the oil pressure, or rather the difference between the oil pressure in pipe 17 and the oil pressure in pipe 23. The result is that the piston responds to the movement of rod 14 whereas the rod 14 could exert only a relatively small pressure on piston 13, but a large pressure is now exerted and so the throttle 5 opens until the pressure in the pipe 18 is large enough to generate sufficient supercharger pressure in chamber 12 to oppose the compression of the spring 10 when the diaphragm 11 and the rod 14 move into their neutral positions and the throttle 5 ceases to open. The liquid entering at 17 flows through a port 43, which engages with a groove 44 in the rod 14. When rod 14 is moved

to the left, the oil under pressure is thus admitted to chamber 24 from the port 44 through ports 45, 46 and 47.

When the rod 14 is moved to the right, oil under pressure in groove 44 flows into chamber 25 along ports 48, 49 and 26. Meanwhile, the liquid from the opposite side of piston 13 escapes to the outlet 23 as follows: when piston 13 is moved to the left by oil pressure in 24 as a result of moving rod 14 to the left, then port 48 is put in communication with a groove 52 in rod 14, which is in communication with a port 53, which is connected with the outlet port 23.

When piston 13 is moved to the right by oil pressure in 25 as a result of moving rod 14 to the right, a groove 50 in rod 14 is put in communication with the port 45 and so through the port 51 with the outlet port 23.

The casings A and B, as well as the housing 54 containing the chamber 12, are all stationary.

Altitude control

The roller 8, which acts as the pivot for lever 3, is held in engagement with the cam 7 by the spring 27. The expansion of the barometric element 6 moves valve rod 28 to the right which permits oil pressure to escape from the right hand side of piston 29 to pipe 31. Oil pressure is then admitted through a pipe 30 to the left hand side of piston 29. The piston 29 then rotates the cam 7 clockwise. The piston 29 is pushed to the left by the compression spring 39 and pushes the yoke 38 to the right and thus pushes the rod 40, which engages with a slot 42 in the lever 7, which has a fulcrum 41 in the stationary element 37. A groove 55 in piston 29 is in communication with the low pressure pipe 31. When valve 28 moves to the left, the pressure in chamber 56 to the left of piston 29 falls to the pressure in pipe 31 due to the restriction 57. 58 is a corresponding restriction between the high pressure line 30 and the chamber 59 to the right of the piston 29.

When starting the engine, before oil pressure becomes available, the spring loaded element 32 locks the cam 7 in place so that until oil pressure is obtainable, the fulcrum 8 is held in a fixed position. Oil pressure admitted from pipe 30 unseats the locking device 32.

Operation

Whenever the throttle valve 5 is in equilibrium, that is to say, when the pressure in the inlet manifold 19 is high enough to balance the compression of the spring 10 determined by the position of the manual control lever 1 and the altitude cam 7, the diaphragm 11 is in the position shown in the drawing. Hence, the spring 10 is compressed against the flange of the rod 14 which assumes a fixed position whenever the throttle 5 is in equilibrium. Hence, the position of the lever 3 determines the position of the throttle 5 and the position of the lever 3 is determined jointly by the position of the manual control lever 1 and the position of the altitude cam 7 which automatically increases the gauge pressure with altitude. More specifically, the position of the lever 3 determines the differential pressure between the manifold air pressure and this pressure differential is modified by the lever 1 manually and by the barometric capsule 6 automatically through the cam 7.

What I claim is:

1. A throttle control for a supercharged aircraft engine comprising an air entrance to said engine, a throttle valve therein, a lever therefor,

a chamber, a moving wall associated therewith, a passage connecting said chamber with the engine side of said supercharger, spring loading means engaging with said moving wall in opposition to the supercharger pressure, the pressure on the other side of said wall being atmospheric, manually controlled means for controlling said spring loading means, barometric responsive means for modifying said spring load on said moving wall at all positions of said manual means, a connection from said moving wall to said throttle lever whereby the position of the throttle is controlled by the movement of said moving wall in response to changes in the pressure of the supercharger and this supercharger pressure is balanced by said spring loading means which is regulated jointly by the manual control means and by said barometric means.

2. A device as set forth in claim 1 in which a servo motor is interposed between said movable wall and said throttle.

3. A device as set forth in claim 1 in which a servo motor is interposed between said barometric means and said spring loading means.

4. A device as set forth in claim 1 in which a servo motor is incorporated in said connection from said moving wall to said throttle and in which a servo motor is incorporated between said barometric responsive means and said spring loading means.

5. A throttle control for a supercharged aircraft engine comprising an air entrance to said engine, a throttle valve therein, a lever therefor, an air chamber, a moving wall associated with said chamber, operative means connecting said wall with said throttle lever, a passage connecting said chamber with the engine side of said supercharger, spring means engaging with said wall, the pressure on the other side of said wall being atmospheric, a control lever engaged with said spring means, manually controlled means for moving said lever, barometric responsive means for varying the fulcrum of said control lever whereby the spring load on said movable wall is regulated jointly by the manual control means and by said barometric control means and the throttle lever is opened and closed until the supercharger pressure balances said spring load.

6. A throttle control for a supercharged aircraft engine comprising an air entrance, a throttle valve therein, a lever therefor, a servo motor having a piston connected to said lever so constructed and arranged as to open and close said throttle, an air chamber, a moving wall associated therewith, a passage connecting the air chamber with the engine side of said supercharger, a valve controlling said servo motor, said valve being connected to said moving wall, spring loading means associated with said moving wall, the pressure on the other side of said wall being atmospheric, a control lever engaging with said spring loading means, a barometric responsive device, a servo motor associated therewith and connected to the fulcrum of said control lever, manual means for moving said lever whereby the spring loading means is controlled both manually and automatically.

7. A device as set forth in claim 6 in which the servo motors are so constructed and arranged that in the absence of oil pressure to operate said servo motors, the first servo motor is operated mechanically by said moving wall and the moving wall is positively moved by said control lever and the second servo motor is inoperative 70 to move said fulcrum.

8. Throttle control for supercharged aircraft engines comprising, yielding means, throttle control means responsive to said yielding means and to the amount of supercharger pressure- relative to the atmospheric pressure, said super- charger pressure being arranged so as to act in opposition to said yielding means, an induction throttle valve for said engine connected to said throttle control means, so that an increase in supercharger pressure closes the throttle valve, means responsive to changes in the atmospheric pressure, so constructed and arranged as to vary the said yielding means directly, and thus indirectly the supercharger pressure opposed thereto, so as to vary the position of said throttle valve with altitude, manual means so constructed and arranged as to cooperate with said atmospheric pressure responsive means in the control of said yielding means directly and thus indirectly of said supercharger pressure so that at any given altitude the throttle is closed by said supercharger pressure as said pressure rises above that of said yielding means selected by said manual control means to oppose said supercharger pressure.

9. Yieldable throttle control means for super- charged aircraft engines comprising, a manually operated lever, yielding means associated therewith, throttle control means responsive to the said yielding means and to the amount of super- charger pressure relative to the atmospheric pressure, said yielding means being adapted to oppose said supercharger pressure, an induction throttle valve for said engine connected to 10 said control means, so that an increase in the yielding means opens the throttle, and an increase in the supercharger pressure closes the throttle, means responsive to changes in the atmospheric pressure, so constructed and arranged as to vary 15 said yielding means and the said supercharger pressure, so as to vary the position of said throttle valve with altitude at every position of said manual control means, manual control means so constructed and arranged as to cooperate with 20 said atmospheric pressure responsive means in the control of said yielding means and of said supercharger pressure.
